Des. 204,999
Patented June 7, 1966

204,999

AUTOMOBILE SERVICE TRAY

Lloyd D. Edwards, Rock Island County, Ill.
(2715 46th St., Rock Island, Ill.)

Filed Aug. 16, 1965, Ser. No. 86,605

Term of patent 14 years

(Cl. D44—10)

FIG. 1

FIG. 2

FIG. 3

FIG. 1 is a perspective view of an automobile service tray showing my new design;

FIG. 2 is a plan view of the service tray;

FIG. 3 is a section along the line 3—3 of FIG. 2.

I claim:

The ornamental design for an automobile service tray, as shown.
